[57] CLAIM

The ornamental design for a combined squeegee and sponge for cleaning showers, as shown and described.

DESCRIPTION

FIG. 1 is a perspective view of a combined squeegee and sponge for cleaning showers showing my new design;

FIG. 2 is a front elevational view thereof;

FIG. 3 is a side elevational view thereof, the opposite side being a mirror image;

FIG. 4 is a rear elevational view thereof;

FIG. 5 is an end elevational view thereof; and,

FIG. 6 is an elevational view of the opposite end thereof.

FIG. 1

FIG. 3

FIG. 2

FIG. 5

FIG. 6

FIG. 4
